United States Patent Office

Des. 178,507

Patented Aug. 14, 1956

178,507

DIAL FOR VISUAL FOOTAGE INDICATION

Harlan John Eastman, Denver, Colo., assignor to The Star Recorder Corporation, Denver, Colo., a corporation of Colorado

Application October 22, 1954, Serial No. 32,772

Term of patent 14 years

(Cl. D52—1)

Fig. 1

Fig. 2

Figure 1 is a front elevational view of a dial for visual footage indication showing my new design; and Figure 2 is an edge view thereof.

I claim:

The ornamental design for a dial for visual footage indication, as shown.
